UNITED STATES PATENT OFFICE.

MATTHEW ARNOLD TAYLOR, OF LOS ANGELES, CALIFORNIA.

STAMP-AFFIXING DEVICE.

Application filed February 9, 1923. Serial No. 618,081.

To all whom it may concern:

Be it known that I, MATTHEW ARNOLD TAYLOR, a citizen of Canada, and a resident of Los Angeles, in the county of Los Angeles, State of California, have invented a certain new and Improved Stamping-Affixing Device, of which the following is a full, clear, and exact description.

This invention aims to provide a novel and improved device for holding a plurality of postage stamps in strip arrangement and for supplying a single stamp and affixing the same to a piece of mail matter on each operation of the device.

As preferably embodied, the invention includes an exceedingly simple, inexpensive, compact and reliable device for thus handling postage stamps,—to provide such a device being one object of the invention.

Another object of the invention is to provide a stamp affixing device as indicated wherein the important and practical feature is incorporated of insuring always that irrespective of the speed of movement of the

main actuating part, preferably a palm-knob at the top of a vertically reciprocable frame member or structure, and irrespective of whether or not such frame element is given its full predetermined working stroke or a fraction thereof, only one of two things may occur, to wit, the failure entirely to feed and affix a stamp, or the feeding and affixing of a single whole stamp. In other words, assuming the supply stamp-strip is properly

set after being placed on the supply reel, or on or in some other means having an equivalent function, it is never possible so to actuate the frame element, either by hand or power means, as to sever a stamp from the strip other than along a separating line of perforations or the like between two adjoining stamps, or otherwise mutilate a stamp.

A further object is to provide equally simple, inexpensive, compact and reliable stamp-affixing means, co-acting in timed relation with the other elements of the device, and so co-acting properly to moisten each stamp as it is about to be affixed, and only then.

Various other objects and advantages will be in part obvious and in part pointed out below.

The invention will be best understood from a consideration of the following detailed description when taken in connection

with the accompanying drawing forming part of this specification; with the understanding, however, that such drawing illustrates, merely by way of example, one possible embodiment of the invention, and that the invention is not confined to any strict conformity with the showing in the drawing, but may be changed and modified so long as such changes and modifications mark no material departure from the salient features of the invention as expressed in the appended claims.

In said drawing,

Fig. 1 is a vertical section through the device taken on line 1—1 of Fig. 2 with certain parts broken away;

Fig. 2 is a vertical section taken on line 2—2 of Fig. 1, also with certain parts broken away;

Fig. 3 is a vertical section taken on line 3—3 of Fig. 2; and

Fig. 4 is a very much enlarged fragmentary view showing certain of the parts as seen in Fig. 1.

A sheet metal main-frame structure to various parts of which the reference character 5 is applied in Figs. 1, 2 and 3, includes a top cross-piece 5^a having near opposite ends a pair of parallel lateral slots. Through these slots are guided upper vertically extending portions of a sheet metal slide-frame structure to various parts of which the reference character 6 is applied in Figs. 1, 2 and 4.

Slide-frame 6 is further guided by a slot engagement with a fixed horizontal rod 7; the slide-frame being identically slotted on opposite sides as indicated at 8.

Slide-frame 6 is held normally elevated as shown by means of an expansile spring 9 between it and the main-frame; and such slide-frame may be manually depressed for a stamp-affixing stroke by means of a palm or striker-knob 10 at the top of the device and fixedly upstanding from the upper cross length of the slide-frame.

Fixed rod 7 is mounted by a threaded connection at one end in the main-frame as indicated at 11, and at its opposite end carries a reduced cylindrical portion marked 7^a in Fig. 2 and set loosely in an accomodating axial recess in the inner end of a stub shaft 12 journaled in that side of the main-frame.

This arrangement securely sets the rod 7 fixedly in place and at the same time permits a gear 13 pinned as indicated in Fig. 2 to

the inner end of the stub shaft to be rotated independently of a reel 14 loose on rod 7 between the gear and the far side of the main-frame.

5 This reel on which the supply strip 15 of stamps is wound is turned pursuant to the action of a rubber or other suitable roller 16 relative to the lower portion of the strip; such roller being fixed on the same shaft 17 as is secured a pinion 18. Shaft 17 is journaled in main frame 5.

The parts are so designed that on each $\frac{1}{6}$ revolution of gear 13 by the action of a flat spiral spring 19 (Figs. 2 and 3) when the 15 gear is released for such a fractional revolution by a rocking of a lever 20 to free its lower claw 21 relative to one of the six co-acting latch projections 14^a on gear 13, the strip 15 is fed by roller 17 the distance of 20 a full width or length of a stamp. In the present case it is preferable to use strips 15 in each of which the stamps of the column are arranged side by side; that is to say, the reel 14 is of a slightly greater 25 length than that of a stamp, and the distance the roller 17 feeds the strip each time the gear 13 makes a complete $\frac{1}{6}$ revolution, is equal to the width of a stamp plus the space between two adjoining stamps.

30 Such spring 19 has its inner end set tight in a suitable jam-notch 22 (Fig. 3) cut in stub-shaft 12; the other end of the spring being secured to a pin 23 fixedly offset from a cup-hood 24 having a central opening as 35 clearly shown in Fig. 2 by way of which a bolt 25 (Fig. 2) may be set in the outer end of the stub shaft to secure the hood in place but loose relative to the stub-shaft.

Thus, whenever the spring 19 needs to 40 be rewound it is only necessary to rotate the hood about the stub shaft, as by means of a knob 26 (Fig. 2) formed integral with pin 23; pawl and latch means as indicated at 27 being provided to prevent unwinding of the 45 spring by way of a reverse movement between hood and stub shaft.

Lever 20 is pivoted to its side of the main frame as at 28. As indicated most clearly 50 in Fig. 4, the upper substantially horizontal arm 20^a of the lever is slightly rockable relative to the longer arm of the lever, in the direction indicated by the arrow 29, against a wire spring 30. This result is attained by having the relatively movable arm parts 55 of the lever shaped in the vicinity of pivot 28 so as to overlap each other and so as to present mutually limiting portions or shoulders as indicated at A and B in Fig. 4.

A portion of slide-frame 6 reciprocable in 60 line with the free end of arm 20^a of lever 20 is provided with a ratchet projection 31.

Where strip 15 is acted on by roller 16, such strip is guided in a chute formed by a pair of plate members 32 (Fig. 1). This 65 chute is fixedly carried by a detachable

water cup 33, preferably shaped as indicated, and including an extra inner wall most removed from the main-frame, comprising a sheet-like wick 34 of any suitable material. It will be noted that this wick 70 emerges from the lower thin elongate mouth of the cup 33 in such a way as to permit water to exude from the cup by way of such mouth only as the result of capillary action in the wick; and that the wick is protruded 75 beyond such mouth to present an area forming one of the side walls of the chute at the extreme lower end thereof. The water cup 33 may have a hinged cover 35.

The water cup and chute structure just 80 described are carried by the main structure, detachably if desired, by the hook engagement of a notched plate 36 on the cup and a pin 37 carried by the main-frame. It will be noted in this connection that the 85 weight distribution of the parts hanging from pin 37 is such that the uninterrupted plate 32 of the chute is forced to a certain pressure against roller 16 and thereby the parts are disposed as illustrated in Fig. 1. 90

Operation: Assume that the machine has just been set up, that is to say, the cup 33 has been filled with water, and a strip 15 of stamps has been wound on the reel as 95 illustrated but with the forward or lower edge E of the strip not as shown in Fig. 1 but at the point E'.

On striking knob 10 to depress the slide-frame, tooth 31, if the slide-frame is depressed far enough, rocks lever 20 to release gear 13 for a one-sixth revolution, for a full movement to that extent, and only for a full movement. Thus one stamp, the one at the lower end of the strip, is fed, fully fed, and solely fed, after being moistened by wick 34. Such stamp now lies as shown in Fig. 1, that is, extends from the point E' to the point E, but still unsevered from its fellows. Thus it will be seen that such a feeding of a single stamp occurs on a downward movement of the slide-frame even short of its full stroke, provided only such movement is sufficient to rock lever 20. On the other hand it will be seen that any movement of the slide-frame less than that required to rock lever 20, will result in no feeding movement at all of the strip 15. If a downward movement of frame 15 results in a feeding of a stamp as described, and such movement is a full stroke, the stamp will be affixed to the piece of mail matter by the impact of the striker plate formed by the bottom cross-length of the slide-frame. If, however, after such a single stamp has been fully fed during the first part of a downward stroke of the slide-frame, the slide-frame is inadvertently not given its full stroke, the subsequent withdrawal of the piece of mail matter will show the same unstamped, whereupon the moistened stamp is manually pulled free and af- 125

fixed to the piece of mail matter in the usual way. It will of course be understood that when the stamp is affixed by the device, the same will be severed from its fellows along 5 a proper line of separation, by means of the lower edge of the striker plate adjacent to the lower end of cup 33, practically at the instant the stamp is automatically affixed.

On the ensuing upstroke of the slide-frame 10 in response to spring 9 projection 31 freely passes lever 20 without moving claw 21 due to the permitted relative movement of the arms of such lever. As the projection passes the free end of arm 20^a, said arm momen- 15 tarily rocks upward relative to the other arm of lever 20 to separate the shoulders B and advance the shoulders A toward each other. As soon as the projection 31 clears the free end of arm 20^a, spring 30 restores the lever 20 arms to the positions illustrated.

I claim:

1. In a device of the kind described, the combination of means for feeding a strip of stamps, an actuator movable to operate such 25 means to feed such strip to dispose a portion thereof in position to be severed and affixed to a piece of mail matter, means for moistening such portion during the feeding operation, means for severing such portion, 30 means for affixing the severed portion to said piece, and means for controlling the feeding means, whereby to prevent any feeding at all of such strip on a movement of such actuator less than a predetermined minimum 35 and for insuring the complete feeding of a single stamp on a movement of such actuator greater than such minimum and less than the full movement of the actuator required to affix a stamp.

40 2. The device defined in claim 1, wherein said severing and affixing means are portions of a single striker plate fixed relative to said actuator.

45 3. The device defined in claim 1, wherein said severing and affixing means and the actuator are carried by a single slide-frame, and said stamp-feeding means includes a gear and a reel, there being provided a fixed frame for guiding the slide-frame on which 50 said gear and reel are rotatably mounted.

55 4. The device defined in claim 1, wherein said feeding means includes a gear and means associated with the gear and the actuator for fractionally rotating the gear on each full working stroke of the actuator.

60 5. The device defined in claim 1, wherein said feeding means includes a gear and means associated with the gear and the actuator for fractionally rotating the gear on each full working stroke of the actuator, said feeding means further including a reel

for the strip, and means for co-axially mounting reel and gear for dissimilar angular speeds of rotation simultaneously.

6. The device defined in claim 1, wherein 65 said feeding means includes a gear having a plurality of latch members, means for urging the gear to revolution, and a pivoted member rockable by the actuator and on each rocking of which is adapted to free one 70 of said latch members and thereupon engage another latch member.

7. The device defined in claim 1, wherein 75 said feeding means includes a guide chute for the strip and said moistening means includes a wick forming a wall of said chute.

8. The device defined in claim 1, wherein 80 said feeding means includes a guide chute for the strip and said moistening means includes a wick forming a wall of said chute at the lower end thereof.

9. In a device of the kind described, the combination of means for feeding a strip of stamps, an actuator movable to operate such 85 means to feed such strip to dispose a portion thereof in position to be severed and affixed to a piece of mail matter, means for moistening such portion during the feeding operation, means for severing such portion, 90 means for affixing the severed portion to said piece, said feeding means including a gear fractionally rotated on each full working stroke of the actuator, and a loose reel co-axial with the gear.

10. In a device of the kind described, the combination of means for feeding a strip of stamps, an actuator movable to operate such 95 means to feed such strip to dispose a portion thereof in position to be severed and affixed to a piece of mail matter, means for moistening such portion during the feeding operation, means for severing such portion, 100 means for affixing the severed portion to said piece, said feeding means including a gear fractionally rotated on each full working 105 stroke of the actuator, and a supply reel for the strip controlled by said gear.

11. In a device of the kind described, the combination of means for feeding a strip of stamps, an actuator movable to operate 110 such means to feed such strip to dispose a portion thereof in position to be severed and affixed to a piece of mail matter, means for moistening such portion during the feeding operation, means for severing such portion, 115 means for affixing the severed portion to said piece, said feeding means including a gear fractionally rotated on each full working stroke of the actuator, a supply reel for the strip, and means whereby the movement of the reel is controlled by said gear.

MATTHEW ARNOLD TAYLOR.
